UNITED STATES PATENT OFFICE.

FRED N. LA CHAPELLE, OF BEVERLY, MASSACHUSETTS, ASSIGNOR TO UNITED SHOE MACHINERY COMPANY, OF PATERSON, NEW JERSEY, A CORPORATION OF NEW JERSEY.

PRESSER-FOOT MECHANISM FOR SEWING-MACHINES.

1,234,913.

Specification of Letters Patent. Patented July 31, 1917.

Application filed July 23, 1910. Serial No. 573,365.

To all whom it may concern:

Be it known that I, FRED N. LA CHAPELLE, citizen of the United States, residing at Beverly, in the county of Essex and State of Massachusetts, have invented certain new and useful Improvements in Presser-Foot Mechanism for Sewing-Machines; and I do hereby declare the following to be a full, clear, and exact description of the invention, such as will enable others skilled in the art to which it appertains to make and use the same.

The present invention relates to a device for lifting the presser-foot of a sewing machine.

The present invention as embodied in the mechanism herein described is intended as an improvement upon the machine shown and described in the patent to French & Meyer, No. 473,870, April 26, 1892, and has for its object the release of the presser-foot upon the reversal of the driving shaft. In practice, the operator, when it is desired to remove the work from the sewing machine, reverses the rotation of the driving shaft until the needle and awl are pulled from the work, and it is the usual practice to so position the clamping bolt of the pulley wheel upon the driving shaft that when the shaft is turned in position to free the work of the awl and needle that said clamping bolt will be on the top of the shaft, the operator watching the position of the bolt to determine when the work may be removed from the machine. In the Goodyear outsole rapid stitcher, described in the above-mentioned French & Meyer patent, it is usual to employ the presser-foot releasing device shown and described in the patent to Holmes, No. 584,039, June 8th, 1897, by which when the operator desires to remove the work he may do so by releasing the presser-foot by means of a hand lever. In my improved device it is possible for the operator to release the presser-foot by hand at any stage of the stitch-forming operation, and I also provide means whereby upon the reverse rotation of the driving shaft, the presser-foot will be automatically released from the work, and this automatic release of the presser-foot may be arranged to take place at a time when the awl and the needle are removed from the work.

My invention also contemplates certain other features of construction particularly defined in the claims.

In the drawings accompanying this application I have illustrated the particular form of my invention as applied to the well-known Goodyear rapid stitcher, which is illustrated in the above-mentioned patent to French and Meyer. It will be understood, however, that my invention is equally applicable to other types of sewing machines, and that it can be otherwise embodied without departing from the spirit of my invention.

Referring to the drawings, Figure 1 is a side elevation, taken partly in cross section, of the mechanism embodying my invention; Fig. 2 is a side elevation showing in more detail the presser-foot arm and its releasing link, while Fig. 3 shows the releasing link alone.

Referring to Fig. 1 of the drawings indicates a work support against which the work is held by a presser-foot 2 which is carried by an elbow-shaped lever 3 which is loosely mounted to turn about the stud 4, which is mounted upon the frame of the machine. Pivoted on the stud 4 is the arm 5 which is yieldingly connected with the elbow-shaped lever 3 by means of the spring 6 and link 7. At the ends of the arms 3 and 5 are the ratchet toothed surfaces 8 and 9 respectively. The ratchet teeth 9 are engaged by a pawl 10 borne upon the end of a lever 11, said lever being pivoted to the frame at 12 and oscillated by a cam roller 13 running in a cam slot formed in the side of the cam wheel 14. The upward movement of the lever 11, transmitted to the arm 5 by means of the pawl 10 and ratchet 9, raises the arm 5, putting the spring 6 under compression, and by means of the link 7 and arm 3, forcing the presser-foot 2 upon the work, the presser-foot being firmly held in position by means of the ratchet teeth 8 which are engaged by one or more of the pawls 15, varying preferably in length to thus provide in the usual manner for finer adjustments, said pawls being pivoted upon a stud 16 rigidly secured to the frame. Secured to the pawl 15 is the upwardly extending arm 17 and also the horizontally disposed pin 18. Borne upon the rear end of

arm 3 is the bearing stud 19 to which is attached the sliding frame 20 used in varying the stroke of the pull-off, the frame 20 being held upwardly by a light spring 21. The path of the cam roller 13 is so timed with relation to the operation of the needle and awl that during the feeding of the work the presser foot is relieved of the pressure of the spring 6, but when the work is stationary the spring 6 is compressed to force the presser foot against the work to clamp it on the work support. With the exception of the arm 17, the purpose of which will be hereinafter explained, the arrangement and operation of the foregoing parts is substantially that disclosed in the above-mentioned French and Meyer patent and Holmes patent, and further detailed description is considered unnecessary. It will be noted, however, that with my device applied to the Goodyear rapid stitcher shown in the French and Meyer patent, the lever and cam roller designated at f^{15} and f^{16} respectively in the French and Meyer patent, are placed above the driving shaft as indicated at A and B in my drawings to allow space for the releasing link in my device to engage below the driving shaft.

Pivoted about the stud 4 is a lever 22 bearing the handle 23. Pivoted to the lower extremity of the lever 22 is a bifurcated link 24, the lower rearwardly extending arm of this link being forked to engage and be guided by the pin 18 upon the pawl 15 while the upper rearwardly extending arm of this link strikes against a pin 25 carried by a pawl 10. When the handle 23 is drawn forward the link 24 pushes the pawls 15 and 10 from engagement with the ratchets 8 and 9, and allows the presser-foot to be lifted by hand by means of a handle 26. This form of hand release for the presser-foot is similar to that disclosed in the Holmes patent, except that the link 24 is bifurcated to release both arms 3 and 5 and allow the operator to lift the presser-foot without having to compress by hand the spring 6 as necessary in the device disclosed in the Holmes patent.

Keyed upon the driving shaft 27 is the hub 28 of the cam wheel 14 and extending to the right of the cam wheel viewing the machine from the front. This hub is longitudinally slotted or recessed at 29, one edge of the slot or recess forming the ratchet tooth or edge 33. Loosely lying against the hub 28 is the upper end of a link 30. The upper end of the link 30 bears a curved finger 31 of the curvature similar to the circumference of the hub 28. The upper end of the link 30 at a point near the branching off of the finger 31 is formed with a pawl tooth 32 which is arranged to be engaged by a single ratchet tooth 33 formed on the hub 28. The bottom of the recess which is cut in making this tooth 33 is padded with a

cushion of leather or other soft material 34 to prevent rattling of the link 30 as it drops into this recess during the normal rotation of the driving shaft as indicated by the arrow in Fig. 1. When the driving shaft is running in its normal direction of rotation the ratchet tooth 33 will slip over the pawl 32. When, however, the direction of rotation of the driving shaft 27 is reversed, the ratchet tooth 33 will engage the pawl 32 and force the link 30 downward, the curved finger 31 forming a bearing against the hub 28 and holding the upper end of the link 30 in position beneath the shaft 27. The lower end of the link 30 is bifurcated to form a slot 31^a in which is engaged the pin 19 borne by the presser-foot arm 3. There is also formed upon the lower end of link 30 a lug 35 recessed to hold one end of a spring 36 whose other end is borne by the frame 20, this spring serving as a yielding support for the link 30. The upward thrust of the spring 36 is resisted by a stop 36^a limiting the upward movement of the link 30, the action of the spring 36 and stop 36^a exerting a torque to hold the upper end of the link 30 in engagement with the hub 28. Secured to the link 30 near its lower end is a bearing shoulder 37 which, when the link 30 is forced downwardly, will engage the upward end of the arm 17 and by a cam action force it to the rear, releasing the pawl 15 from the ratchet teeth 8.

The operation of my device is as follows: When the driving shaft is reversed the ratchet tooth 33 engages the pawl 32 carrying the link 30 downwardly. The link 30 in its downward movement first compresses the spring 36, then the shoulder 37, striking the arm 17, releases the pawl 15 from the ratchet teeth 8 and the stud 19, slipping in the slot 31^a, is finally engaged at the upper end of the slot, and the arm 3 forced downwardly against the force of the spring 6, thus lifting the presser-foot 2, the parts assuming the position shown in Fig. 2. It will be noted that the pawl 10 still engages the ratchet teeth 9 so that the spring 6 is compressed by the downward movement of the arm 3. The work may now be easily removed from beneath the presser-foot 2 when the needle and awl are withdrawn from the work by the backward rotation of the driving shaft. By suitably positioning the notch 29 about the shaft 27, the presser-foot may be lifted at that point in the reverse rotation at which the needle and awl are withdrawn from the work. A new piece of work may now be placed upon the work support beneath the presser-foot and the driving shaft started in its normal direction of rotation. The upper end of the link 30 is now carried upwardly and to the left from the position shown in Fig. 2, thus allowing the presser-foot to again descend upon the work, the

spring 6 forcing the presser-foot down with the same force that it had before the presser-foot was automatically released by the reverse rotation of the shaft, a result which it 5 was impossible to obtain when the operator was compelled to replace the force of the spring upon the presser-foot by hand.

Having now described my invention what is claimed is:—

10 1. A sewing machine having, in combination, stitch forming and work feeding devices, a driving shaft, a relatively movable work support and presser foot, yielding means inoperative during the feeding of the 15 work but acting at times when the work is stationary to force the work support and presser foot together to clamp the work between them, and means operating in timed relation with the stitch forming and work 20 feeding devices made operative only upon the reversal of the rotation of the driving shaft for separating the work support and presser foot against the pressure of said yielding means, whereby the work may be withdrawn, 25 substantially as described.

2. A sewing machine having, in combination, stitch forming and work feeding devices, a driving shaft, a relatively movable work support and presser foot, yielding means inoperative during the feeding of the work but acting at times when the work is stationary to force the work support and presser foot together to clamp the work between them, means for locking the work 30 support and presser foot against the work, and means operating in timed relation with the stitch forming and work feeding devices made operative only upon the reversal of the rotation of the driving shaft for unlocking said locking means and for separating the work support and presser foot against the pressure of said yielding means, whereby the work may be withdrawn, substantially as described.

35 3. A sewing machine having, in combination, stitch forming and work feeding means, a driving shaft, a work support, a movable presser foot, a spring acting with a heavy pressure to force the presser foot 40 against the work on the work support when the work is stationary, means for relieving the work of the pressure of the spring when the work is fed, and means operating in timed relation with the stitch forming and 45 work feeding devices made operative by the reversal of the rotation of the driving shaft for lifting the presser foot against the force of the spring, whereby the work may be withdrawn, substantially as described.

50 4. A sewing machine having, in combination, stitch forming and work feeding devices, a work support, a movable presser foot, a weak spring acting with a normally light pressure to force the presser foot 55 against the work on the work support, means

including a strong spring inoperative during the feeding of the work but acting at times when the work is stationary to increase the pressure of the presser foot against the work, and means made operative by the reversal of the rotation of the driving shaft to lift the presser foot against the pressure of said second spring, whereby the work may be withdrawn, substantially as described.

5. A sewing machine having, in combination, stitch forming and work feeding devices, a driving shaft, a work support, a movable presser foot, means including a spring inoperative during the feeding of the work but acting at times when the work is stationary to force the presser foot against the work on the work support, means operating in timed relation with the stitch forming and work feeding devices made operative only upon the reversal of the rotation of the driving shaft for lifting the presser foot against the force of the spring whereby the work may be withdrawn, said means upon the resumption of rotation of the driving shaft in normal direction automatically allowing the spring to again force the presser foot against the work, substantially as described.

6. A sewing machine having, in combination, stitch forming and work feeding devices, a driving shaft, a relatively movable work support and presser foot, a spring, means acting through the spring to clamp the work between the work support and presser foot once during each cycle of stitch forming operations and acting to release the work when it is fed, and means operating in timed relation to the stitch forming and work feeding devices inactive during the normal operation of the machine and made operative only upon the reversal of the rotation of the driving shaft for separating the work support and presser foot against the pressure of the spring, substantially as described.

7. A sewing machine having, in combination, stitch forming and work feeding devices, a relatively movable work support and presser foot, a spring for holding the presser foot and work support in light engagement with the work, a second and stronger spring, means acting through the second spring to clamp the work between the work support and presser foot once during each cycle of stitch forming operations and acting to release the work when it is fed, and means inactive during the normal operation of the machine and made operative only upon the reversal of the rotation of the driving shaft for separating the work support and presser foot against the pressure of the second spring so that the work may be removed and having provision for automatically allowing the spring to again clamp the work between the work support

and presser foot upon the resumption of rotation of the driving shaft in its normal direction, substantially as described.

8. In a sole-sewing machine, the combination with a drive shaft, a work support and a movable presser-foot, of operating means, inoperative when said drive shaft moves in its normal direction, but operated upon reversal of said shaft for raising said presser-foot, said operating means being so constructed and arranged to become disconnected from said shaft after said presser-foot is raised, and constructed to leave said presser-foot in raised position.
- 15 9. In a sole-sewing machine, the combination with a drive shaft, a work support, and a movable presser-foot, of a member connected with said presser-foot, and operating means on said shaft engaging said member upon reversal of said shaft, constructed and arranged to raise said presser-foot and thereafter become disconnected from said member to leave said presser-foot in raised position.
- 20 10. A sewing machine having, in combination, a driving shaft, a tooth connected with the shaft, a presser foot, a work sup-

port, mechanism including a disconnecting link constructed and arranged to engage the tooth upon rotation of the driving shaft in reverse direction to raise the presser foot and upon continued rotation of the driving shaft in reverse direction to become disconnected from the tooth and leave the presser foot in raised position.

35 11. A sewing machine having, in combination, a driving shaft, a tooth connected with the shaft, a presser foot, a work support, presser foot raising mechanism including a disconnecting link constructed and arranged to engage the tooth upon rotation of the driving shaft in reverse direction to raise the presser foot and upon a continued rotation of the driving shaft in reverse direction to become disconnected from the tooth after the presser foot is raised, and means for holding the presser foot in raised position upon a continued rotation of the driving shaft in reverse direction.
